UNITED STATES PATENT OFFICE

JOHN R. MACKINNON, OF BOSTON, MASSACHUSETTS

DOOR-SECURING DEVICE

Application filed April 22, 1927. Serial No. 185,835.

My invention relates to locks, and particularly to that form of a door securing device which when operatively engaged will permit the door to be partially opened.

The invention will be best understood from the following description when read in the light of the accompanying drawing of a specific embodiment of the invention selected for illustrative purposes, while the scope of the invention will be more particularly pointed out in the appended claims.

In the drawing:

Fig. 1 is a view looking into the casing of the locking mechanism with the cover removed;

Figs. 2 and 3 respectively are sections on the lines 2—2 and 3—3 of Fig. 1;

Fig. 4 shows a detail of the locking mechanism;

Fig. 5 is a detail of the right hand part of Fig. 2 on an enlarged scale;

Fig. 6 is a section corresponding to the right hand part of Fig. 3 showing the locking bar in position to enter the casing;

Fig. 7 shows a detail; and

Fig. 8 shows the device assembled on a door and door frame.

Referring to the drawing I have herein shown a locking mechanism having a casing 1 mounted on a door 3, while adapted to engage with said locking mechanism is a bolt in the form of a bar 5 carried by a support 7 mounted on the frame 9 of the door.

As illustrated the bar 5 at one end is provided with a spherical head 11 slidably mounted in the support 7, the body of the bar extending through the slotted wall 13 of said support so that the bar can both slide in said support and swing in a horizontal plane. At its opposite end the bar is provided at opposite sides with grooves 15, thus forming a head 17 on that end of the bar.

The bottom of the casing 1 at the end thereof adjacent the edge of the door is herein provided with a T-shaped opening having the inner enlarged portion 19 and outer narrow portion 21 respectively corresponding to and adapted to receive the head 17 of the bar and that portion of the bar 5 between the grooves 15, this construction providing that when

the door is closed to move the casing 1 toward the projecting end of the bar said end will enter the opening in the casing.

In said casing adjacent the opening for the bar is a segmental member 23 pivoted at 25 on a plate 27 supported on and projecting upward from the bottom wall of the casing. At the end thereof above the opening for the bar the member 23 is provided with a cam surface 29 adapted to be struck by the bar 60 when the latter enters the casing so as to turn the member 23 on its pivot counterclockwise as viewed in Fig. 6. The end of the member 23 opposite the cam plate 29 bears against the abutment surface 31 of a slide 33 guided upon the bottom of the casing. As shown in Fig. 4 the member 33 at its right hand end is in the form of a flat slotted plate 35 the sides of which when the slide is moved to the right by engagement of the bar with the cam plate 29 cover those portions of the part 19 of the opening for the bar which extend beyond the edges of the part 21 of said opening. This will prevent removal of the bar from the casing and lock it securely thereto. As illustrated in Figs. 3 and 6 the side of the casing adjacent the opening for the bar is slotted as indicated at 37, the width of the slot 37 corresponding to the width of that portion of the bar which is between the 80 grooves 15. This construction permits the door to be opened a distance determined by the length of the bar.

As illustrated the member 33 is provided with laterally placed notches 39 the upper of which cooperates with a detent 41 mounted for sliding movement in upper guides 43. A spring 45 is provided for urging the detent toward the member 33 so that when the latter is slid to the right as viewed in Fig. 1 the 90 detent 41 will snap into the notches 39 and hold the plate in its right hand position, in which position the end of the bar cannot be removed from the casing.

As illustrated, near the left hand end of the casing is shown a block 45 mounted for sliding movement in a lower guide 47 carried by the casing, this block being urged to the right as viewed in Fig. 1 by a spring 49. Carried by the block 45 and movable therewith is a 100

cam member comprising a rod 51 and the two cam portions 53, the upper portion 53 as shown in Fig. 1 being adapted to contact the right hand end of a lower arm 55 when the block 45 is slid to the left. The lower rod 55 as shown is part of an integral structure which includes a similar upper rod 55, the left hand ends of these rods being connected by being formed integrally with a sleeve 57 rotatably mounted on a post 59 secured to the bottom wall of the casing 1. By this construction when the block 45 is moved to the left and the upper cam portion 53 contacts the lower rod 55, the upper rod 55, which 15 is pivotally secured in any suitable manner to the detent 41, will raise the detent from the notch 49 to permit the plate 33 to be moved to the left. Herein for moving the plate 33 to the left block 45 has an upwardly 20 projecting portion 59, the upper end of which as shown in Fig. 1 lies between the shoulders 61 (Fig. 4) of the member 33, the construction being such that after the detent 41 is lifted from the notch 39 the projection 59 25 will contact the left hand shoulder 61 and move the slide 33 to the left.

As illustrated the casing 1 is provided with a tubular extension 63 having fixed therein a key controlled lock 65 provided with a rotatable barrel 67 actuated by the removable key 69. In alignment with the barrel is a rotatable spindle 71 having the flattened end 73 adapted to engage with a slot 75 in the end of the key barrel so that when the latter is rotated the spindle will be rotated with it. Carried by the spindle is an arm 77 adapted to engage with the surfaces of the right hand notch 79 formed in the sliding block 45, with the result that when the key is inserted and 40 the barrel of the lock rotated the arm 77 will be moved clockwise as viewed in Fig. 1 to move the block 45 to the left and thereby move the sliding block 33 to the left and permit removal of the bar 5 from the casing. As 45 shown in Figs. 2 and 5 the spindle 71 at the inner side of the door projects through the wall of the casing and carries a knob 81, which knob may be slid longitudinally of the spindle to a limited extent determined by the pin 50 and slot connection 83, 85 between the knob and spindle. Pulling the knob away from the casing, after the lost motion connection provided by the pin and slot connection is 55 taken up, will move the spindle outward to compress the spring 87 which urges the spindle toward the key barrel, and withdraw the flattened end 73 of the spindle from the slot 75 in the end of the key barrel. This will both 60 render the key inoperative to actuate the mechanism and permit the spindle to be rotated by means of the knob 81. This construction as is obvious permits the mechanism to be unlocked by use of the key, or by use of 65 the knob on the inside of the door, and also

provides that when desired the key controlled mechanism is rendered inoperative.

As shown the end of the spindle 71 is provided with opposite laterally arranged notches 89 which carry spring clips 91. When the knob is pulled away from the casing as shown in Fig. 5 the spring clips are released and the ends thereof move past the peripheral wall of the spindle and engage with the exterior wall of the casing 1, which holds the spindle in its withdrawn position. Forcing the knob inward compresses the clips 91 and allows the spring 87 to move the spindle inward so as to engage it with the key barrel.

As illustrated the notches 39, guides 43 and 47, cams 53, etc., are made in duplicate at opposite sides of the center lines of appropriate parts of the device to permit rearrangement to adapt the device for use on doors which swing clockwise and counter-clockwise. This provides that if the casing is reversed from the position shown by Fig. 1 the block 45 and detent 41 may be placed in the upper guides 47 and 43 shown by that figure, which guides in the reversed position of the casing will then become the lower guides. Similarly the spindle 71 may be rotated 180 degrees from the position shown and the other parts appropriately changed.

Although I have described for purposes of illustration one particular embodiment of my invention it is to be understood that within the scope of the invention wide deviations may be made without departing from the spirit of the invention.

Claims:

1. A door locking mechanism having, in combination, a bolt adapted to be slidably carried by a part which is stationary relative to said door, locking mechanism carried by said door, said locking mechanism and bolt being so constructed that when said door is closed the end of said bolt will engage with said mechanism and automatically actuate it into locked position, said mechanism permitting relative movement of said bolt when locked thereto whereby said door may be opened partially and closed, and manually actuated means for releasing said bolt from said mechanism with the door closed.

2. A door locking mechanism having, in combination, a bolt, means slidably carrying said bolt for limited movement relative to a part which is stationary relative to said door, locking mechanism adapted to engage and automatically lock said bolt to said door when the latter is closed whereby said door may be only partially opened, key controlled mechanism for actuating said locking mechanism into unlocked position from one side of said door with the latter closed, and manually actuated means for actuating said locking mechanism into unlocked position from the other side of said door.

3. A door locking mechanism having, in combination, a bolt, means slidably carrying said bolt for limited movement relative to a part which is stationary relative to said door, locking mechanism adapted to engage and automatically lock said bolt to said door when the latter is closed whereby said door may be only partially opened, key controlled mechanism for actuating said locking mechanism into unlocked position from one side of said door, and means operative from the other side of said door for rendering said key controlled mechanism inoperative.

4. A door locking mechanism having, in combination, a bolt, means slidably carrying said bolt for limited movement relative to a part which is stationary relative to said door, locking mechanism adapted to engage and automatically lock said bolt to said door when the latter is closed whereby said door may be only partially opened, key controlled mechanism for actuating said locking mechanism into unlocked position from one side of said door, and means operative from the other side of said door for rendering said key controlled mechanism inoperative and also for actuating said locking mechanism into unlocked position.

5. A door locking mechanism having, in combination, a bar, locking mechanism for cooperation with said bar, said bar and mechanism being so constructed that one may be carried by said door and the other by a part which is stationary relative to said door, means for slidably supporting said bar, said locking mechanism comprising a casing having an opening which said bar is adapted to enter, and means in said casing cooperating with the end of said bar for preventing withdrawal of said end from said casing.

6. A door locking mechanism having, in combination, a bar, locking mechanism for cooperation with said bar, said bar and mechanism being so constructed that one may be carried by said door and the other by a part which is stationary relative to said door, means for slidably supporting said bar, said locking mechanism comprising a casing having an opening which said bar is adapted to enter, means in said casing cooperating with the end of said bar for preventing withdrawal of said end from said casing, said last named means being actuated by insertion of said end into said opening.

55 7. A door locking mechanism having, in combination, a bar, locking mechanism for cooperation with said bar, said bar and mechanism being so constructed that one may be carried by said door and the other by a part which is stationary relative to said door, means for slidably supporting said bar, said locking mechanism comprising a casing having an opening which said bar is adapted to enter, means in said casing cooperating with 60 the end of said bar for preventing withdrawal

of said end from said casing, said last named means being actuated by insertion of said end into said opening, and key controlled means for rendering said means inoperative.

In testimony whereof, I have signed my name to this specification.

JOHN R. MacKINNON.
